(57) **CLAIM**

The ornamental design for a waste management device, as shown and described.

DESCRIPTION

FIG. 1 is a perspective view of a waste management device made in accordance with the subject design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof; and,

FIG. 8 is a bottom view thereof.

The broken lines in the drawings show portions of the waste management device, which form no part of the claimed design.
